UNITED STATES PATENT OFFICE

128,038

DESIGN FOR A TEXTILE FABRIC

Elsie J. Das, Honolulu, Territory of Hawaii, assignor to Watumull Brothers, Honolulu, Territory of Hawaii, a firm

Application May 5, 1941, Serial No. 100,791

Term of patent 7 years

To all whom it may concern:

Be it known that I, Elsie J. Das, a citizen of the United States, residing at Honolulu, in the county of Honolulu, Territory of Hawaii, have invented a new, original, and ornamental Design for Textile Fabrics, of which the following is a specification, reference being had to the accompanying drawing, forming part thereof.

In the accompanying drawing the figure is a plan view of a piece of textile fabric showing my new design, the unit of which is contained between the dot and dash lines, the same being repeated in regular succession as indicated by the extensions beyond the unit boundaries.

I claim:

The ornamental design for a textile fabric, substantially as shown and described.

ELsie J. Das.
